UNITED STATES PATENT OFFICE.

JOSEPH M. DELMORE, OF PIRU, CALIFORNIA.

UNDERREAMER.

1,006,446.

Specification of Letters Patent. Patented Oct. 17, 1911.

Application filed September 28, 1910. Serial No. 584,371.

To all whom it may concern:

Be it known that I, JOSEPH M. DELMORE, a citizen of the United States, residing at Piru, in the county of Ventura and State of California, have invented a new and useful Underreamer, of which the following is a specification.

The main object of the present invention is to provide an underreamer which will present cutting surfaces covering substantially a complete circle, thereby obviating the liability of the underreamers to cut a flat or non-circular hole and insuring the formation of a hole which will allow free descent of the casing.

A further object of the invention is to provide an underreamer in which the several parts are located in operative position in such manner as to form a substantially rigid structure.

Another object of the invention is to provide means for retaining the cutters and their supporting members in place during the operation, the retaining means being reusable when required to remove the cutters.

Other objects of the invention will appear hereinafter.

The accompanying drawings illustrate the invention, and referring thereto: Figure 1 is a vertical section of the underreamer in operative position. Fig. 2 is a similar view showing the underreamer in collapsed position and entered within the casing. Fig. 2^a is a vertical section of the underreamer with the parts in position for withdrawal of the cutters from the body of the tool. Fig. 3 is a horizontal section on line x^3-x^5 in Fig. 1. Fig. 4 is a horizontal section on line x^4-x^4 in Fig. 1. Fig. 5 is a vertical section of the upper part of the device at right angles to Fig. 1, showing the parts in position for releasing the cutters. Fig. 6 is a vertical section of a retaining plate for the underreamer cutters. Fig. 7 is an inverted plan thereof. Fig. 8 is a vertical section of the means for supporting said plate.

1 designates the body of the underreamer which is tubular and is adapted to enter freely within the casing 2, said tubular body 1 being adapted to be secured by screw socket 1', in the usual manner, to the lower end of the usual operating means 2' therefor. The lower end of the tubular member 1 is formed with a frusto-conical recess 3 adapted to receive and fit the upper ends of the cutters 4 when said cutters are in oper-

ative position. Said cutters are held in such position by locking means consisting of a bar 5 slideable in a partition or flange 6 extending at the lower end of the axial recess 60 7 in the tubular member 1, said bar 5 carrying at its upper end a head 8 engaged by a spring 9 whose lower end engages with the flange 6 aforesaid, so as to tend to raise said bar, and said bar being provided at its lower 65 end with means for engaging the several cutters 4. Bar 5 is square or non-circular and the hole in flange 6 is correspondingly formed to prevent rotation of said bar. Head 8 is fast on bar 5, being, for example, 70 screwed on said bar 5, and held by jam nut or screw collar 8'.

The cutters 4 are segmental in cross section and are of such circumferential length as to extend substantially around a complete circle. Any desired number of cutters may be used, three being the preferred number, each cutter being then approximately 120° in segmental length. I prefer to use three or more cutters for the reason that the 80 cutters will then move in different radial directions, the angles between said directions being less than 180°, so that as the cutters move inwardly and outwardly, they do not move directly but obliquely to and 85 from one another, and the circumferential separation of their outward movement is therefore less than when they move directly to and from one another. Consequently with three or more cutters, the cutters when 90 in operative expanded position present less space between them than is the case with only two cutters and extend substantially around the complete circle so that the possibility of cutting a flat hole is avoided. 95 The cutters 4 are provided with cutting edges 4' at their lower ends and with faces 10 at their upper portions formed as co-noidal segmental surfaces adapted to fit within the frusto-conical recess 3 aforesaid, and the upper ends of the cutters 4 are adapted 100 to fit against the upper end of said recess, the top of said recess being preferably dished slightly upward and the cutters being inclined upwardly and inwardly at their upper ends in correspondence therewith. At the lower ends of the bearing surfaces 10 the cutters are formed with shoulders 11 adapted to engage under the lower end of the tubular body 1 and at a lower point on 110 the cutters there is provided on the outside of the cutters an enlargement or shoulder

- 12 adapted to engage with the lower end of the casing as the cutter is being drawn thereinto. The inner faces of the cutters converge or taper inwardly and upwardly, 5 as shown at 13, such converging portions terminating in vertical faces 14 adapted to fit the respective sides of a polygonal block 15 on the lower end of the bar 5. With the stated construction in which three cutters 10 are provided, this block is preferably of triangular cross section having three flat faces 15' engaging with the respective faces 14 of the cutters. A spring 16 bears against this block and against a ring 17 slidably mounted on the bar 5, said ring 17 engaging with grooves 18 in the cutters to hold the cutters in place, as hereinafter set forth.
- I prefer to provide means whereby the locking bar is retained or prevented from 20 moving downwardly to more than a limited extent in the ordinary operation of the device, so that there is no possibility of the cutters 4 becoming loose or detached in such operation. Such retaining means comprises 25 a plate 20 slidably and non-rotatably mounted on a squared stud portion 21 at the upper end of the locking bar 5 above the head 8 thereon, said plate 20 having projections or lugs 23 adapted to extend over a shoulder 30 24 on the tubular body 1 and the stud 21 having a nut 25 screwing on the upper end thereof and engaging over the plate 20, so that the downward movement of the locking bar 5 is limited by the engagement of said 35 nut with the plate 20 and of the lugs 23 on said plate with the shoulder 24. Vertical slots 33 are provided in the tubular body 1 extending downwardly from the shoulder 24 a sufficient distance to allow the lugs 23 to pass downwardly when in register therewith, so as to allow the locking bar to drop far enough for release of the cutters 4 from the recess 3. In order to release this retaining means when it is desired to detach the 40 cutters, the plate 20 is provided with a cap 26 secured thereto as by rivets 26' and extending over the nut 25 and stud 21, said cap 26 having a central tapped hole 27 adapted to receive a bar 28 (see Fig. 5) 45 which is inserted through a longitudinal bore 28' in the locking bar 5 said bore extending through block 15 and being screw threaded to receive an eyebolt 32 (Fig. 2^a). The stud 21 is provided below the squared 50 portion thereof with a rounded portion 30 to enable the plate 20 to be drawn down off of said squared portion, and a spring 31 is provided seated against the head 8 and engaging said plate 20 to normally raise said 55 plate into position surrounding the squared portion 21. In the normal position of the parts shown in Fig. 1, the plate 21 will be held somewhat above the shoulders 24, so that the lugs 23 on said plate are separated 60 from said shoulder. By inserting the bar 65 28 aforesaid through the bore 28' and screwing it into the hole 27 and then drawing down on said bar, the plate 20 may be pulled off of the squared portion of the stud 21 and may then be turned a quarter turn bringing its lugs 23 in line with the slots 33 in the tubular body 1. The locking bar 5 with the parts carried thereby, including the cutters, and the locking block 15 are then drawn down sufficiently (as shown in Fig. 2^a) to allow the cutters to be slipped out from within the recess 3, the bar 28 being first withdrawn and an eye-bolt, indicated at 32, being screwed into the lower end of bore 28' in block 15 to draw the said block, bar 5 and head 8 downwardly. The said bar 28 is of sufficient length to enable it to extend up in the bore 28' into engagement with the tap hole 27, while its lower end projects below the bottom of the underreamer into position to be grasped by the hands of the operator and the eye-bolt 32 is also of sufficient length to enable it to extend into position to be grasped by the operator. The cutters are recessed above the vertical walls 14, as shown at 29, to provide a space for receiving the parts above described and to receive the block 15 when the same is elevated, as hereinafter set forth. The shoulder 29' at the bottom of recess 29 and the lower face 14' of block 15, are preferably inclined to enable the said block to be pushed into position between the flat faces 14 of the cutters by the action of the spring 16.
- In entering the underreamer into the casing, the cutters are gripped by suitable means and drawn outwardly so as to enable the shoulder 29' to slip over the outer end of the block 15 and to enable said block to enter recess 29 and the cutters to be collapsed into position, (shown in Fig. 2), in which they may be entered within the casing. In this operation the spring 16 is compressed and the spring 9 is also compressed, the bar 5 being drawn downwardly within the body 1. The underreamer is then entered within the casing, and while it is passing through the casing, the cutters are held in collapsed position by engagement of the shoulders 12 with the wall of the casing. When the underreamer reaches the bottom of the casing, the cutters are forced outwardly by the action of the inclined faces of the block 15 and shoulders 29' this action being produced by the pressure of spring 16 which moves the block 15 into position between the vertical faces 14 of the cutters, as shown in Fig. 1. At the same time the spring 9 moves the cutters and bar 5 bodily upward, causing the upper portions or shanks of the cutter to be seated in the conical recess 3 of the body 1. When the blocks are moved outwardly, as stated, to operative position shown in Fig. 1, the 13

shoulders 11 are under the tubular body 1, their bearing faces 10 fit within the frustoconical seat 3 in the tubular member 1 and their upper ends 24 fit against the dished 5 upper end of the said recess. As the triangular block 15 fits tightly against the several cutters, it is apparent that the cutters are located in tight contact with the tubular body 1 forming a substantially rigid 10 structure. Tight contact at the upper ends of the cutters is insured by the ring 17, the spring 16 operating through said ring 17 to press the cutters upward and cause their upper ends to bear upwardly and outwardly 15 on the walls of the recess 7. In withdrawing the underreamer tension is exerted on the tubular body 1, in the usual manner, to draw the cutters upwardly within the casing, and on account of the outward flare of 20 the cutters, the ascent of the cutters is resisted by reason of the engagement of the cutters with the casing and as the upward movement of the tubular body 1 is continued, said body moves away from the cutters, the springs 9 and 16 being compressed 25 and the bar 5 being drawn upwardly until the locking block 15 at the lower end thereof snaps into the interior recess 29 within the cutters. This removes the obstruction 30 to the inward movements of the cutters and in the farther upward movement of the tubular member 1 the cutters are collapsed by the engagement of their outwardly flaring outer faces with the casing 2, so that the 35 underreamer as a whole may be withdrawn through the casing 2.

What I claim is:

1. An underreamer comprising a tubular body having a recess in its lower end, three 40 or more cutters, seated in said recess, said cutters extending in conjunction throughout a complete circle, and mounted to move in different directions, the angles between said directions being less than 180° , and 45 said cutters being formed interiorly with vertical faces and with recesses above said vertical faces, in combination with a locking member 50 slidably vertically within said body, and provided at its lower end with a block adapted to fit between the vertical faces of the cutters to hold the cutters outwardly to operative position, and to move upwardly into said recesses to allow the cutters to move inwardly, and means inter- 55 posed between said cutters and said locking bar to raise and lower the cutters by operation of the locking bar, and to allow limited relative movement of the cutters and locking bar.

2. An underreamer comprising a tubular body having a recess in its lower end, a plurality of cutters seated in said recess, said cutters extending in conjunction substantially throughout a complete circle, and being formed interiorly with vertical faces, 60 and with recesses above said vertical faces, in combination with a locking bar slidable vertically within said body, and formed at its lower end with a block adapted to fit between the vertical faces of the cutters to hold the cutters outwardly to operative position, and to move upwardly into said recesses to allow the cutters to move inwardly, a member slidable on the locking bar, and 65 engaging the upper portions of the cutters to raise and lower the cutters by operation of the locking bar, and a spring interposed between said member and said locking bar to force the cutters upward.

3. In an underreamer, the combination 80 with a tubular body having a recess at its lower end and a plurality of cutters having their upper portions seated in said recess, of a locking bar slidably mounted in said tubular body and provided with means for 85 engaging said cutters to hold the same within said recess, a spring tending to hold said locking bar in elevated position, retaining means mounted at the upper end of said locking bar and provided with projecting 90 means, said tubular body having a shoulder adapted to be engaged by said projecting means to limit downward movement of said locking bar and having slots to receive 95 said projections in a certain position there- 10 of to permit farther downward movement for release of the cutters, said retaining member being movable to bring the said projecting means thereon into and out of co- operative relation with said slots in the tubular body.

In testimony whereof, I have hereunto set my hand at Los Angeles, California, this 20th day of September, 1910.

JOSEPH M. DELMORE.

In presence of—
